ENGINE-DRIVEN GENERATOR FOR CHARGING BATTERIES

Howard C. Napier, 909 S. Gilbert,
Anaheim, Calif. 92804

Filed Apr. 7, 1967, Ser. No. 6,589

Term of patent 14 years

(Cl. D26—15)

FIG. 1.

FIG. 2.

FIG. 3.

FIG. 4.

FIGURE 1 is a perspective view of an engine-driven generator for charging batteries, embodying my new design;

FIGURE 2 is an end elevation thereof, showing the end not shown in FIGURE 1;

FIGURE 3 is a top plan view thereof; and

FIGURE 4 is a rear elevational view thereof.

The broken lines of an engine are for illustrative purposes only. The bottom of the apparatus is plain.

I claim:

The ornamental design for an engine-driven generator for charging batteries, substantially as shown and described.
